United States Patent Office

Des. 197,233
Patented Dec. 31, 1963

197,233

FENCE

Irving R. Burnstine, 1830 NE. 163rd St.,
North Miami Beach, Fla.

Filed Mar. 7, 1963, Ser. No. 73,977

Term of patent 14 years

(Cl. D28—1)

FIG. 1

FIG. 2

FIG. 3

FIG. 5

FIG. 4

FIG. 1 is a front elevation view of a fence showing my new design, the rear thereof being the same in appearance;

FIG. 2 is a top plan view;

FIG. 3 is a bottom plan view;

FIG. 4 is an end elevation view; and

FIG. 5 is an enlarged sectional view taken on the line 5—5 of FIG. 1.

The dominant features of this design reside in the portions shown in full lines.

I claim:

The ornamental design for a fence, as shown and described.
